PROJECTION SYSTEM

James H. S. Hamer, Brooklyn, N. Y., assignor to
Trans-Lux Daylight Picture Screen Corpora-
tion, New York, N. Y., a corporation of Dela-
ware

Application August 12, 1932, Serial No. 628,531

5 Claims. (Cl. 88—24)

My invention relates to a projection system for obtaining images of characters or representations on a tape, or equivalent.

My invention, in one prominent phase thereof, relates to a projecting system wherein the projecting light beam passes substantially vertically and coacts with a horizontally movable character-bearing tape, the light beam thereafter being separated into individual light beams to simultaneously produce duplicate images of the same character.

My invention, in other phases, thereof, relates to a projection system involving plural light-reflecting arrangements of simple character and high efficiency.

Various other objects, advantages and characteristics of my invention will become apparent from the following description taken in connection with the accompanying drawing.

20 My invention resides in the projection or reflecting system, features and arrangement of parts of the character hereinafter described and claimed.

25 My invention relates particularly, but not necessarily, to a projection or reflecting system utilizable with projection mechanism of the general character disclosed in the copending Halloran application Serial No. 373,767, filed June 26, 1929 and which has become Patent No. 1,952,249 dated 30 March 27, 1934.

For an understanding of my invention and for an illustration of some of the many forms thereof, reference is to be had to the accompanying drawing, in which:

35 Figure 1 is a diagrammatic, perspective view of a projection system arranged in accordance with my invention;

Fig. 2 is a plan view of a part of the projection system shown in Fig. 1;

40 Fig. 3 is an elevational view, partly in section, of a part of the projection system shown in Fig. 1; and

Fig. 4 is a perspective view showing another form of my invention.

45 Generally, in accordance with a preferred form of my invention, ordinary transparent or semi-transparent ticker tape emanating from stock ticker mechanism is passed by any suitable mechanism horizontally and flatwise through a projection field with the inked surfaces forming the characters facing upwardly. By any suitable arrangement, a projecting light beam is caused to traverse the section of the tape within the projection field in substantially a vertical direction, the light beam thereafter being deflected so as to partake of movement substantially in a horizontal direction. While thus moving horizontally, said light beam, after it has traversed a suitable objective lens, is brought into coacting relation 50 with a suitable arrangement for producing or

obtaining independent light beams, the latter, respectively, passing to separate screens to cause the simultaneous image display of those tape characters then in the projection field.

More specifically, as shown in Figs. 1, 2 and 3, 5 an arrangement constructed in accordance with my invention may comprise a suitable source of light A such, for example, as an incandescent electric lamp, light from which may pass substantially horizontally through one lens L of a suitable condensing lens system. The light beam after traversing the lens L and while passing substantially horizontally engages a mirror or other suitable reflecting member M to cause said light beam to pass substantially vertically first through another 10 lens L₁ of the condensing lens system and then through any suitable aperture I formed or constituted by a member 2, said aperture I defining the projection field of the projection system and with respect to which the tape T is movable in 15 the direction of the arrows, Figs. 1 and 2, after said tape leaves the ticker mechanism, not shown. As shown, the characters on the tape T are written and readable lengthwise thereof.

With the form of my invention shown in Figs. 25 1, 2 and 3, the projection light beam is deflected from its substantially vertical course after leaving the projection field by a prism P which, obviously, may be replaced by a mirror or any other suitable reflector. From the prism P, the light 30 beam passes substantially horizontally and traverses a suitable objective lens L₂ after which said light beam is separated into independent light beams in any suitable manner.

As herein shown although not necessarily, the 35 arrangement for obtaining independent light beams comprises crossed mirrors M₁ and M₂ arranged at angles of 90 degrees with respect to each other and at angles of 45 degrees with respect to the axis of the light beam traversing the 40 objective lens L₂ whereby the independent light beams pass laterally in opposite directions and at angles of 90 degrees with respect to the axis of said light beam traversing the objective lens L₂. However, the angular relation of the mirrors 45 M₁ and M₂ with respect to each other and with respect to the axis of said light beam may be varied from that stated in a desired manner whereby the independent light beams are obliquely related to the axis of the light beam traversing the 50 objective lens L₂.

With the form of my invention shown in Figs. 1, 2 and 3, the independent light beam reflected by the mirror M₁ passes more or less horizontally to a mirror M₃ and then more or less vertically to a mirror M₄, the latter reflecting said light beam preferably in substantially a horizontal direction to a suitable screen S. Similarly, the other independent light beam passes more or less horizontally to a mirror M₅, then more or less 60

vertically to a mirror M_6 and then substantially horizontally to a screen S_1 .

With the form of my invention herein shown the screens S and S_1 are of the character adapted for "rear" projection wherein the projecting light beam passes through the screen in order to reach the audience, the images being readable by observation of the front of each screen. With an arrangement of the character described, the images appear on the respective screen S and S_1 in vertical position and in the same order as the characters are printed on the tape T , said images on the respective screens simultaneously passing in opposite directions in correspondence with the tape movement. The screens S and S_1 should be disposed substantially vertically and preferably they are in substantially parallel relation, the length of the light paths between each screen and the objective lens L_2 being approximately equal.

In the form of my invention shown in Fig. 4, the light beams after leaving the respective mirrors M_1 and M_2 pass directly and without reflection to the respective screens S and S_1 . Under most circumstances, the use of a system of the character shown in Fig. 1 is desirable and advantageous. However, at times, it may be desirable to use the simpler and more efficient projection arrangement of Fig. 4.

In Fig. 4, the optical system for the main light beam prior to engagement thereof with the crossed mirrors M_1 and M_2 may be the same as shown in Fig. 1. However, as shown in Fig. 4, the prism P is replaced by a mirror M_7 and the objective lens is placed in the vertical part of the light beam path rather than in the horizontal part thereof. It shall be understood, if desired, that the optical system just described may be substituted for the corresponding parts of the generally equivalent system of Fig. 1.

While the invention has been described with respect to certain particular preferred examples which give satisfactory results, it will be understood by those skilled in the art after understanding the invention, that various changes and modifications may be made without departing from the spirit and scope of the invention and it is intended therefore in the appended claims to cover all such changes and modifications.

What is claimed as new and desired to be secured by Letters Patent is:

1. In a projection system, the combination with a plurality of spaced screens disposed in substantially vertical back-to-back relation, of a projection field with respect to which a tape having characters reading lengthwise thereof is horizontally movable while disposed flatwise, said projection field having its longer dimension disposed transversely of the planes of said screens and said tape following the course defined by said projection field whereby the path of tape movement is transversely disposed with respect to the planes of said screens, means for passing a projecting light beam upwardly through said projection field and the tape section defined thereby, and means for obtaining on said screens images of the tape characters which move horizontally in correspondence with movement of the tape, said last named means comprising an objective lens traversed by said light beam and an arrangement for dividing said light beam into separate beams which pass to said screens, respectively.

2. In a projection system, the combination with

a plurality of spaced screens disposed in substantially vertical relation, of a projection field with respect to which a tape having characters reading lengthwise thereof is horizontally movable while disposed flatwise, said projection field having its longer dimension disposed transversely of the planes of said screens and said tape following the course defined by said projection field whereby the path of tape movement is transversely disposed with respect to the planes of said screens, means for passing a projecting light beam upwardly through said projection field and the tape section defined thereby, and means for obtaining on said screens images of the tape characters which move horizontally in correspondence with movement of the tape, said last named means comprising an objective lens traversed by said light beam and an arrangement for dividing said light beam into separate beams which pass to said screens, respectively, the light beam traversing said objective lens passing substantially horizontally to said dividing arrangement.

3. In a projection system, the combination with a plurality of spaced screens disposed in substantially vertical relation, of a projection field with respect to which a tape having characters reading lengthwise thereof is horizontally movable while disposed flatwise, and means comprising duplicate light-reflecting systems and an objective lens for obtaining on said screens images of the tape characters which move horizontally in correspondence with movement of the tape, said objective lens being traversed by a light beam emanating from said projection field, each light-reflecting system, beyond said objective lens, having less than four mirrors.

4. In a projection system, the combination with a plurality of spaced screens disposed in substantially vertical relation, of a projection field with respect to which a tape having characters reading lengthwise thereof is horizontally movable while disposed flatwise, and means comprising duplicate light-reflecting systems and an objective lens for obtaining on said screens images of the tape characters which move horizontally in correspondence with movement of the tape, said objective lens being traversed by a light beam emanating from said projection field, each light-reflecting system, beyond said objective lens, having but one mirror.

5. In a projection system, the combination with a plurality of spaced screens disposed in substantially vertical back-to-back relation, of a projection field with respect to which a tape having characters reading lengthwise thereof is horizontally movable while disposed flatwise, said projection field having its longer dimension disposed transversely of the planes of said screens and said tape following the course defined by said projection field whereby the path of tape movement is transversely disposed with respect to the planes of said screens, and means comprising duplicate light-reflecting systems and an objective lens for obtaining on said screens images of the tape characters which move horizontally in correspondence with movement of the tape, said objective lens being traversed by a light beam emanating from said projection field, said reflecting systems comprising means for dividing said light beam into separate light beams which pass to the respective screens along separate non-crossing paths.

JAMES H. S. HAMER.
